[57] CLAIM

The ornamental design for front panel for a combined radio receiver and cassette tape player, as shown and described.

DESCRIPTION

FIG. 1 is a top plan view of front panel for a combined radio receiver and cassette tape player showing our new design;

FIG. 2 is a front elevational view thereof;

FIG. 3 is a bottom plan view thereof;

FIG. 4 is a left side elevational view thereof; and

FIG. 5 is a right side elevational view thereof.

The housing shown in broken lines in FIGS. 1 and 3-5 is shown for illustrative purposes only and forms no part of the claimed design.
